INSERT FOR AN ELECTRIC SHAVER CARRYING CASE

John F. Daniels, Bridgeport, and Robert A. Mockovak,
Newtown, Conn., assignors to Sperry Rand Corpora-
tion, New York, N.Y.

Filed Dec. 30, 1970, Ser. No. 26,700

Term of patent 14 years

Int. Cl. D3—02

U.S. Cl. D87—1

FIG. 6.

FIG. 5.

FIG. 4.

FIG. 3.

FIG. 1 is a front perspective view of an insert for an electric shaver carrying case showing our new design;

FIG. 2 is a perspective view thereof similar to that of FIG. 1, a carrying case and transformer being shown in broken lines for illustrative purpose to indicate environment only;

FIG. 3 is a top plan view of the insert;

FIG. 4 is a side elevational view of the insert looking from the left at FIG. 5;

FIG. 5 is a front elevational view thereof; and

FIG. 6 is a side elevational view of the insert looking at the right of FIG. 5.

The back of the insert for an electric shaver carrying case is substantially plain and unornamented.

We claim:

The ornamental design for an insert for an electric shaver carrying case, substantially as shown and described.
